UNITED STATES PATENT OFFICE

1,986,568

ENGINE

James O. Fink, Detroit, Mich., assignor to Continental Motors Corporation, Detroit, Mich., a corporation of Virginia

Application August 24, 1931, Serial No. 558,919

14 Claims. (Cl. 123—171)

My invention relates to engines and more particularly to a fan bracket assembly and means for supporting same on the engine.

An object of my present invention is to facilitate the manufacture and assembly of a fan assembly with an internal combustion engine by providing a novel arrangement for supporting said fan assembly.

A further object of my invention is to construct an economically manufactured fan bracket support by providing a combined fan bracket and water outlet fixture adapted for assembly with an internal combustion engine.

For a more detailed understanding of my invention, reference may be had to the accompanying drawing which illustrates one form which my invention may assume, and in which:

Fig. 1 is a side elevational view of an internal combustion engine illustrating my novel combined fan bracket and water outlet connection secured to the engine.

Fig. 2 is a vertical sectional view through the device taken substantially on the line 2—2 of Fig. 3, and

Fig. 3 is a vertical sectional view taken at right angles to Fig. 2 on the line 3—3 of Fig. 2.

In the illustrated embodiment of my invention I have illustrated my device as assembled with an engine of the sleeve valve type though obviously the principle of my invention may be utilized in connection with internal combustion engines other than those of the sleeve valve type. In the drawing, 10 designates an engine block which is provided with suitable water jackets 11 surrounding the cylinders 12. Cylinder head structures 13 are secured to the engine block and preferably individual cylinder heads are employed for each engine cylinder. A super-structure 14 is secured to the engine block in any suitable manner, in the sleeve valve art this super-structure being known as a cylinder head cover, said structure providing a water jacket portion 15 through which water or other cooling mediums may be circulated. The water jacket 15 is provided with an outlet 16 and my novel combined water outlet connection and fan bracket is adapted to be secured to the cover 14 in any suitable manner such as by bolts or other fastening devices 17. This combined outlet water connection and fan bracket is designated by the reference character A. A radiator 18 having an inlet 19 is associated with the engine, said inlet 19 being connected with the outlet water connection A by means of a flexible rubber hose or other suitable coupling 20.

Figs. 2 and 3 illustrate in detail the construction of the combined water outlet connection and fan bracket. This device or fixture provides a water conduit 21 which is branched as at 22 and forms branches 23 at a point adjacent the lower end of said fixture. These branches 23 communicate with the inlet port 16 and thus the water or other cooling medium may flow through said fixture with a minimum of restriction. The fixture is provided with an elongated opening 24 positioned intermediate the branches 23, this opening preferably extending in a direction substantially parallel to the axes of the branches 23, and is preferably positioned in a manner as shown in Fig. 3 and may be said to be located centrally of the fixture.

A fan assembly B is adapted to be carried by this combined water outlet connection and fan bracket A. The fan assembly includes a fan 25 and a fan pulley 26 suitably secured together and driven from the crankshaft in the usual manner by means of suitable driving connections or belts 27. The fan assembly includes a stud 28 which preferably rotatably supports the fan and fan pulley assembly. This stud 28 is preferably flattened as at 29, and is arranged to be engaged in the elongated opening 24, the flats 29 of said stud engaging the sides of the opening to prevent relative rotation of the stud with respect to said fixture. The reduced end portion 28' of the stud is externally threaded and receives the nut 30.

The fan assembly can thus be secured to the combined water outlet and fan bracket fixture in a plurality of positions since the elongated opening 24 permits the said stud to be moved longitudinally of the opening and secured therein in any adjusted position.

It will be noted that the construction herein described provides a simple means whereby the fan assembly can be supported on the engine and so positioned relative to said engine as to provide efficient air circulation for cooling same.

In sleeve valve engines, it is desirable to have a water outlet connection at the extreme forward end of the engine and generally such a water connection interferes with the fan mounting but by providing a fixture of the character described, I am enabled to assemble a fan assembly with the engine in a manner which does not depart from the recognized practice, and furthermore, the arrangement which I have devised may be more readily manufactured and assembled with an engine. It will be noted that the stud of the fan assembly is secured to said fixture intermediate the branched water passages 23 and can be ad-

justably secured to the fixture in any desired position with a minimum of labor.

Although I have illustrated but one form of my invention, and have described in detail but a single application thereof, it will be apparent to those skilled in the art to which my invention pertains that various modifications and changes may be made therein without departing from the spirit of my invention or from the scope of the appended 10 claims.

What I claim as my invention is:

1. A device of the character described for internal combustion engines and comprising a combined water outlet and fan bracket fixture, said

15 fixture having an opening for receiving a portion of the fan assembly and branched water connections extending on opposite sides of said opening.

20 2. A device of the character described including a water connection adapted to be secured to an internal combustion engine, an engine accessory, said connection having an opening adapted for receiving a portion of said engine accessory and provided with branched water connections extending on opposite sides of said opening.

25 3. A device of the character described including a water connection adapted to be secured to an internal combustion engine and having an elongated opening, an engine accessory, and means adjustably securing said accessory in said opening, said water connection having passages extending on opposite sides of said opening.

30 4. A device of the character described for internal combustion engines and comprising a combined water outlet and fan bracket fixture including fan supporting means located substantially central of said fixture, said fixture including branched water conducting means positioned on opposite sides of said fan supporting means.

35 40 5. A device of the character described for internal combustion engines and comprising a combined water outlet and fan bracket fixture including a water conducting passage, said fixture including an elongated opening having a wall forming a wall of said passage, said opening being adapted for receiving a portion of the fan assembly.

45 50 6. A device of the character described for internal combustion engines and comprising a combined water outlet and fan bracket fixture, said fixture including an elongated opening adapted for receiving a portion of the fan assembly and provided with branched water conducting means positioned on opposite sides of said elongated opening.

55 60 7. A device of the character described for internal combustion engines and comprising a combined water outlet and fan bracket fixture including a water passage, said fixture including an elongated opening and having a wall common to said opening and said water passage, and a fan assembly including a stud for rotatably supporting said fan assembly and having a flattened portion adapted for engagement with a wall of said elongated opening, whereby to secure said stud

against relative rotation with respect to said fixture.

8. A device of the character described for internal combustion engines and comprising a combined water outlet and fan bracket fixture including a water passage, said fixture including an elongated opening positioned substantially centrally of the fixture and extending axially thereof, a fan assembly including a stud for supporting said fan assembly, and means for securing 10 said stud in said elongated opening whereby to position said stud substantially transverse of said water passage.

9. A device of the character described for internal combustion engines and comprising a combined water outlet and fan bracket fixture, said fixture including branched water passages and an opening intermediate said passage, a fan assembly including a stud for supporting said fan assembly, and means for securing said stud 15 in said opening.

10. A device of the character described for internal combustion engines and comprising a combined water outlet and fan bracket fixture, said fixture including branched water passages, 20 a fan assembly, and means securing said fan assembly to said fixture intermediate said branched water passages.

11. A device of the character described for internal combustion engines and comprising a combined water outlet and fan bracket fixture, said fixture including branched water passages, a fan assembly including a stud for supporting said fan assembly, and means for securing said stud to said fixture intermediate said branched water 35 passages.

12. A device of the character described for internal combustion engines and comprising a combined water outlet and fan bracket fixture, said fixture including branched water passages 40 and an elongated opening intermediate said passages, a fan assembly including a stud for supporting said fan assembly, and means for adjustably securing said stud in said elongated opening.

45 13. A combined water outlet and fan bracket fixture for an engine of the water cooled type having a water header extending generally longitudinally of the engine and comprising a connection extending generally upwardly from said header, said connection having an opening located above said header for supporting a portion of a fan assembly, said connection having water passages extending on opposite sides of said opening.

50 55 14. A combined water connection and fan bracket fixture for engines including a water passage extending substantially upwardly from the engine, means carried by said fixture for supporting a fan shaft, said fixture having a wall portion extending substantially transverse to said water passage and which is common to both said water passage and said fan supporting means.

JAMES O. FINK.
